US00D973765S

(12) **United States Design Patent** (10) **Patent No.:** **US D973,765 S**
(45) **Date of Patent:** **** Dec. 27, 2022**

(54) **PRINTING MACHINE**

(71) Applicant: **Top Vending Machine Electronics Co., Ltd.**, Taoyuan (TW)

(72) Inventor: **Yuan-Fong Chang**, Taoyuan (TW)

(73) Assignee: **Top Vending Machine Electronics Co., Ltd.**, Taoyuan (TW)

(**) Term: **15 Years**

(21) Appl. No.: **29/780,574**

(22) Filed: **Apr. 26, 2021**

(51) LOC (13) Cl. **18-99**

(52) U.S. Cl.

USPC **D18/19**

(58) **Field of Classification Search**

(57) **CLAIM**

The ornamental design for a printing machine, as shown and described.

DESCRIPTION

FIG. 1 is a front, top, perspective view of a printing machine showing my design;

FIG. 2 is a rear, top, perspective view thereof;

FIG. 3 is a front elevational view thereof;

FIG. 4 is a rear elevational view thereof;

FIG. 5 is a left elevational view thereof;

FIG. 6 is a right elevational view thereof;

FIG. 7 is a top plan view thereof; and,

FIG. 8 is a bottom plan view thereof.

1 Claim, 8 Drawing Sheets
